J. DWIGHT KELLOGG, JR., OF NORTHAMPTON, MASSACHUSETTS.

Design No. 4,631, dated February 7, 1871.

DESIGN FOR DOVETAILS.

The Schedule referred to in these Letters Patent and making part of the same.

To all whom it may concern:

Be it known that I, J. DWIGHT KELLOGG, Jr., of Northampton, in the county of Hampshire and State of Massachusetts, have invented and produced a new and original Design for Dovetailing Wood; and I do hereby declare the following to be a full, clear, and exact description of the same, reference being had to the accompanying drawings making a part of this specification, in which the figure is a perspective view of a box.

The design consists in scalloping the grooves, as shown at *a*.

I claim as my invention—

The design for dovetailing wood, as herein shown.

J. DWIGHT KELLOGG, Jr.
